UNITED STATES PATENT OFFICE.

ISAAC NASH AND THOMAS BURLEY, OF NEW YORK, ASSIGNORS TO JAMES H. SWIFT, OF SOUTH AMENIA, NEW YORK.

RAILWAY-SIGNAL.

SPECIFICATION forming part of Letters Patent No. 368,680, dated August 23, 1887.

Application filed February 20, 1886. Serial No. 192,735. (No model.)

To all whom it may concern:

Be it known that we, ISAAC NASH and THOMAS BURLEY, both citizens of the United States, and residents of the city, county, and 5 State of New York, have jointly invented certain Improvements in Railway-Signals, of which the following is a specification.

Our invention relates to a combined semaphore and audible signal wherein the setting 10 of the semaphore or visible signal acts to set the mechanism for operating the audible or sound signal, so that the wheel of a passing car or locomotive will sound the latter signal and warn the engineer in case he has not seen 15 the semaphore.

The main object of our invention is to prevent collisions in foggy weather and at night, when the engineer is unable to see the visible signal usually employed.

20 Our invention will be hereinafter fully described, and its novel features carefully defined in the claims.

In the drawings which serve to illustrate our invention, Figure 1 is a front elevation of 25 our signal arranged alongside of a railway, the cross-ties of which are shown in section. Fig. 2 is a plan view, the audible-signal post being in cross-section in line 2 2 in Fig. 1. Fig. 3 is a vertical transverse section in the plane indicated by line 3 3 in Figs. 1 and 2. Fig. 4 is a vertical transverse section in the plane indicated by line 4 4 in Figs. 1 and 2, showing the semaphore in elevation, as seen from an approaching train. Fig. 5 is a detail view of 30 the rear face of the base of the semaphore-post, on a larger scale than the remaining figures. This view illustrates the bell-crank where the operating-rod coming from the audible signal is connected to the semaphore. Fig. 6 illustrates a modified form of the mechanism for 35 changing the direction of the motion at the audible-signal post. This view corresponds to Fig. 2.

We will preface the detailed description of 40 our invention by explaining that we employ by preference a semaphore-signal hinged to a post, and means for elevating or "setting" this signal, so that it will be visible from approaching trains. We usually employ a hand-lever for setting the semaphore. We also 45 employ an audible signal, usually a gong with

a striking apparatus mounted on a post at the side of the track. This signal is operated by the wheels of the locomotive and cars through the medium of a treadle, over the 55 end of which the wheels run when the signal is set. We connect the moving semaphore with the operating-treadle of the audible signal in such a manner that when the semaphore is set it acts through the connecting mechanism to move the end of the gong-operating treadle into the path of the car-wheels, and thus they are caused to sound the signal. When the semaphore is dropped or otherwise rendered invisible, this movement acts to 65 withdraw the end of the gong-operating treadle out of the path of the wheels, and thus no signal will be given to the engineer.

A represents an ordinary semaphore-signal as a whole, and B represents, as a whole, the 70 audible or sound signal. These are shown as arranged at a little distance apart along the track C; but the exact distance is not material. The semaphore-signal comprises the post a, the pivoted signal-arm b, and the lever c, which is connected to the signal-arm b by a connecting-rod, d. The lever c is provided at one end, Fig. 4, with a weight, c', and is coupled at its other end, through the medium of a chain, c'', Fig. 1, and rod c', with an operating-lever, D, pivoted to an upright frame, D', arranged at any suitable distance from the semaphore. When lever D stands as shown in full lines in Fig. 1, the weight c' acts to set the semaphore arm b in its displayed or visible position, as seen in Fig. 4. The chain c'' passes under a guide-sheave, c', so that when lever D is pushed over to the position seen in dotted lines in Fig. 1 the weighted end of lever c will be thrown up and the display end 80 of arm b lowered. This indicates a clear track. 85

We will now describe the mechanism whereby the setting of the semaphore-signal simultaneously sets the audible signal.

The lever c is connected by a rod, e, to the 90 arm f of a bell-crank lever, F, (seen best in Fig. 5,) pivoted to post a on stud f', usually near the ground. The other arm f'' of the bell-crank lever is connected by a rod, g, to the audible signal B, which we will now describe. The signal B comprises a post, j, or other suitable support or frame, on which is 100

mounted a gong, *h*, or other sounding device. The striking mechanism may be of any suitable kind. We have shown a well-known construction in Fig. 3, which comprises a hammer, *p*, provided with an actuating-spring, *q*, and an operating-lever, *o*, provided with the usual hinged trip on its end to engage the heel of the hammer-arm, and with a retracting-spring, *q'*. To the rear end of the operating-lever *o* is loosely coupled the upper end of a slide-bar or connecting-rod, *I*, which is guided in its longitudinal movements in a guide or keeper, *J*, on post *j*. The upward movement of rod *I* sounds the gong by its action on lever *o*.

We will now describe the mechanism whereby the wheel of the car effects the sounding or striking of the gong *h*, and the mechanism whereby the setting of the semaphore controls this last-named mechanism.

G is a plate arranged to slide in guides or ways, or between two of the ties of the track *C* and at right angles to the latter, and *n* is a treadle or lever pivoted in bearings *n'*, mounted on plate *G*.

H is the rear prolongation or arm of treadle *n*, the rear end of which arm loosely engages an aperture, *o'*, in rod *I*. The treadle *n*, when in operative position, (as seen in Figs. 2 and 3,) stands near the rail or track *C*, and the wheel of a passing car strikes on its convex upper surface and depresses it. This depression throws up the rear end of treadle-arm *H*, which drives up the rod *I* and sounds the gong. When plate *G* is moved back in its ways, treadle *n* is carried back or away from the track out of the path of the car-wheel. The arm *H* plays through hole *o'* in rod *I* when the treadle *n* is moved back. To effect

the movement of plate *G* toward and from the track by means of rod *g* from the semaphore, which rod moves in a path at right angles to that of plate *G*, we mount a plate, *E*, to slide in keepers *m* over and across plate *G*, and

couple it to rod *g*. This plate *E* has formed in it an angular slot, *k*, which is engaged by a pin or screw, *l*, that projects upward from plate *G*. The operation is as follows: Normally the parts stand as shown in the drawings—that is to say, the arm *b* of the semaphore projects out at right angles to the post *a*, signifying "danger," and the treadle *n* stands close to the track-rail and in the path of the wheels of a passing train. Should a train pass the audible signal *B*, each wheel will sound an alarm on the gong and warn the engineer, if he has failed to see the semaphore. If the track is clear, the attendant or signal-man will pull over lever *D*, as explained. This movement

will simultaneously turn the semaphore-arm *b* down to a vertical, or nearly vertical, position, and through rod *e*, bell-crank lever *F*, and rod *g*, move plate *E* longitudinally. This movement of plate *E*, owing to the engagement of pin *l* with slot *k*, will move plate *G* away from the track, and with it the treadle *n*, so that a passing train will get no signal.

The continued hammering of the wheels on the treadle will soon wear the treadle out and destroy it if it be left, as in some signal mechanisms, constantly in the path of the wheels; and we consider it one of the important advantages of our signal that the treadle is only thrown or moved into the path of the wheels when the signal is set to "danger."

Although herein represented as an isolated signal, to be set by hand, it will be obvious that our signals may be connected to form a "block system," so called, the semaphore to be set and dropped by passing trains on entering and passing out of the block. We have not considered it necessary to describe any of the various methods of effecting this.

In Fig. 6 we have shown a bell-crank lever, *E*, which performs the same functions as the slotted plate *E*. (Seen in Fig. 2.) The object is to change the direction of the movement of rod *g* and transmit it to plate *G* at right angles, and this will be effected by the lever *E*, which has a slot in its arm that engages the pin or stud *l*.

We do not wish to limit ourselves to the precise construction and arrangement of parts herein shown, as these may be varied to some extent without departing materially from our invention. For example, the rod *I* might be simply coupled to the end of arm *H* and the guide *J* be omitted. The lever or treadle *n* *H* might also be a simple bar in one piece, instead of arm *H* being socketed in the treadle-head, as shown. The construction shown is merely adopted for convenience of manufacture. Other minor changes of construction, all within the knowledge of those skilled in such constructions, may be made without departing from our invention.

Having thus described our invention, we claim—

1. In combination, the sight-signal, its lever *c*, connected with the operating-lever by a suitable operating-rod, the sound-signal, the plate for positively sliding the sound-signal-operating lever toward and away from the track, the said plate being connected with the said sight-signal lever by suitable rods, the sliding plate carrying the sound-signal-operating lever, the sound-signal-operating lever with its treadle-arm, and its gong-operating arm extending in opposite directions from its pivotal support, and suitable connecting mechanism between the said sound-signal-operating lever and the gong, substantially as set forth.

2. The combination, with the sound-signal, its operating-treadle *n* *H*, adapted to receive impact from the tread of the wheel, connecting-rod *I*, and plate *G*, on which said treadle is mounted, the semaphore-signal *A*, and the mechanism, substantially as described, connecting the movable arm of the semaphore with the plate *G*, whereby the movement of the semaphore-arm is transmitted to said plate *G*, substantially as described.

3. The combination, with the sound-signal,

of the sliding plate G, the operating-treadle mounted thereon and connected with the striking mechanism of the signal, the slotted plate E, mounted to slide in guides at right angles to plate G, and the pin or screw *l* in plate G engaging the oblique slot in plate E, whereby the endwise movement of plate E effects the movement of the treadle into or out of the path of the car-wheel, as set forth.

In witness whereof we have hereunto signed to our names in the presence of two subscribing witnesses.

ISAAC NASH.
THOMAS BURLEY.
